UNITED STATES PATENT OFFICE.

ION A. STAFFORD, OF JAMESTOWN, NEW YORK.

METAL DESK.

Application filed October 27, 1919. Serial No. 333,705.

To all whom it may concern:

Be it known that I, ION A. STAFFORD, a citizen of the United States, residing at Jamestown, in the county of Chautauqua and State of New York, have invented new and useful Improvements in Metal Desks, of which the following is a specification.

This invention relates generally to furniture constructed of pressed sheet steel, and more particularly to a table or desk which may be shipped to a customer in a knock-down condition, so as to reduce the cost of shipping the same.

One object of the invention is to produce a light but strong metal desk which may be readily altered by an unskilled owner, to change the arrangement of the drawers, sliding shelves filing compartments, etc., to suit his fancy or convenience, or a changed use of the desk.

A further object of the invention is to permit of readily assembling the desk or changing or replacing any of its parts without using other than the most common tools.

Another object is to provide means for directly connecting the top of the desk to the supporting legs without causing the top to be buckled or distorted.

A further object is to provide simple means for reinforcing or stiffening the top and other parts of the desk.

A still further object is to provide such a construction as will permit of giving all parts of the desk a final coat of enamel or paint prior to the assembling thereof without the liability of scratching the exposed surfaces during the assembling operation.

Additional objects and advantages are hereinafter described in detail.

In the accompanying drawings: Figure 1 is a perspective view of my improved metal desk with some of the parts removed. Figure 2 is a similar view of a shallow drawer. Figure 3 is a perspective view of a deeper filing drawer. Figure 4 is a perspective view of the sliding shelf. Figure 5 is a similar view of the sliding shelf suspension. Figure 6 is a fragmentary perspective view of one of the pedestals. Figure 7 is a similar view of the tie bar or lower drawer strike which connects the front legs of the pedestal. Figure 8 is a fragmentary vertical longitudinal section through one of the pedestals, taken partly on line 8-8, Fig. 6,

and partly on line 8a-8a, Fig. 10. Figure 9 is a horizontal section taken on line 9-9, Fig. 10. Figure 10 is a vertical transverse section through one of the pedestals taken on line 10-10, Fig. 6. Figures 11 and 12 are horizontal sections through one of the rear legs taken on the correspondingly numbered lines in Fig. 6. Figure 13 is a horizontal section of one of the pedestal legs, showing a filler piece having a modified form of return bend flanges. Figure 14 is a fragmentary cross section of a pair of the drawer-slides and the corresponding drawer-guides. Figure 15 is a horizontal section of one of the front legs on line 15-15, Fig. 1. Figure 16 is a similar section on line 16-16, Fig. 8. Figure 17 is a horizontal section on line 17-17, Fig. 8. Figure 18 is a vertical section on line 18-18, Fig. 17. Figure 19 is an enlarged fragmentary perspective view of a modified form of the supporting legs and the drawer strikes. Figure 20 is a perspective view of a modified form of the drawer slides.

Similar characters of reference indicate corresponding parts throughout the several views.

The desk-top which is preferably constructed of sheet metal, is supported by two spaced pedestals or drawer-sections, each comprising a pair of front legs, a pair of rear legs and panels connecting corresponding front and rear legs. The pedestals are identical in construction, and a description of one will therefore apply to both.

Each of the rear legs or posts 20 is preferably constructed of sheet metal of angular or L-shaped cross section throughout its entire length, and comprises a longitudinal vertical wall 21 and a transverse vertical wall 22, both of which extend inwardly from the outer corner of said leg. The inner edges of both of said walls are provided with inwardly-turned return-bend flanges 23, 24, as best shown in Figs. 6, 11 and 12. Engaging said front return-bend flange 23 and adapted to be moved downwardly thereon, is a vertical longitudinal side panel 25 whose rear edge is provided with a vertical return-bend flange 26, which is lapped around said flange 23. To temporarily prevent the upper end of the panel from moving rearwardly out of engagement with the front flange of said leg, in assembling

the parts, a comparatively weak retaining lip 27 may be arranged at the upper edge of said panel, being formed by cutting a short vertical slit 28 in the upper edge of 5 said panel adjacent to the flange thereof and then bending outwardly the upper corner of metal immediately forward of the slit. The rear vertical edge of said lip 28 bears against the front face of the flange 10 23 of the leg and prevents rearward displacement of the panel, while forward displacement is prevented by the flanged interlock or engagement between said panel and said leg. It is not necessary that the 15 panel be provided with the lip 27 prior to assembling the parts, but the panel may be merely provided with the slit 28 and the lip 27 formed after the panel has been properly positioned on the supporting leg. 20 However, this lip is not essential and may be omitted if desired, its function being solely to facilitate the assembling of the desk by temporarily holding the panel in place. 25 Primarily for the purpose of stiffness, the upper and lower horizontal edges of the panel are provided with the inturned horizontal flanges 30 and 31.

The rear legs of each pedestal are connected by a rear panel 32 whose construction is similar to that of the side panel 25 and which is provided at each of its vertical edges with a return bend flange 33, adapted to engage with the flange 24 of the adjacent rear leg 21, as seen in Figs. 6 and 11.

Secured within the lower part of each rear and front leg by spot welds 34 or otherwise, is a vertically disposed locking or abutment plate 35 comprising a longitudinal wing or extension 36 secured to the wall 21 of the leg and a transverse-wing or extension 37 secured to the wall 22 thereof, as shown in Figs. 6, 11 and 12. Formed at the forward end of said longitudinal extension 45 36 is an inwardly turned, transverse abutment flange 38, which bears against the flange 26 of the side panel 25, preventing the lower part of the latter from moving rearwardly out of engagement with the front flange 23 of the leg. Similarly, the lower part of the rear panel 32 is prevented from disengaging from the flange 24 of the leg by a vertically disposed abutment flange 40 turned inwardly at the inner end of the 50 transverse extension 37 of the abutment plate. 55

Below the side and rear panels and adapted to support the same is a vertically disposed filler piece 41 of L-shaped cross section which forms the front and inner sides of the exposed lower part of each rear leg, giving it the smooth finished appearance of a solid square bar and also eliminating objectionable sharp edges which might tear 60 or cut any clothing coming in contact with

them. This filler piece comprises a transverse wall 42 and a longitudinal wall 43. At the outer edge of the transverse wall is formed a vertical return bend flange 44 which engages slidably with the front flange 23 of the rear leg, as shown in Fig. 12. The rear edge of the longitudinal wall 43 is likewise provided with a return bend flange 45 which engages with the flange 24 of said leg. The flanges of the filler piece are 70 retained in engagement with the co-operating flanges of the leg by the same abutment plate 35 heretofore mentioned, said plate extending some distance below the desk panels for this purpose. In Fig. 13 is shown a 80 modified form of return-bend flanges 440, 450, which are provided with additional bends and bear with their outer thin edge against the outer faces of the respective flanges of the leg. 85

The lower end of each rear leg terminates in a foot piece 46 which is preferably a solid casting tapered toward its bottom end, for the sake of appearance. As best shown in Fig. 8, the upper outer corner of the 90 foot piece is provided with a rabbet or shoulder 47 which is adapted to receive and support the walls of both the filler piece 41 and the leg. Inasmuch as the side and rear panels 25 and 32 rest upon said filler piece and the latter rests upon the foot piece 46, it is apparent that all of said parts are solidly supported. The lowermost part of the foot piece 46 is preferably provided with a recess 50 or other means whereby the usual anti-friction roller or caster may be secured to the foot piece. Centrally formed in the lower part of said foot piece 46 is a hole 51 which receives the head of a vertically-disposed 95 clamping bolt 52 provided at its upper end with a screw thread which engages a threaded hole 53 formed centrally in the lower web 54 of a substantially U-shaped cleat 55 having upwardly-extending suspension arms 56. To facilitate the screwing of the clamping bolt 52 into the cleat, a guide socket or 105 depression 49 with its concave surface facing downwardly, is formed in said web concentrically with the hole 53. At the upper ends of said arms are formed horizontal, 110 outwardly-extending flanges 57 which are secured directly to the lower face of the desk-top 58 by spot welding or other means. These flanges rest on the upper end of the adjacent leg, so that the downward strain 115 or draft caused by the tightening of the clamping bolt 52 is received solely by said cleat, thus relieving the comparatively thin and flexible desk-top therefrom and avoiding all liability of buckling it. The de- 120 pressed body-portion of the cleat fits snugly inside of the leg and is completely enclosed by it, the cleat bearing against two sides of the leg, as shown in Fig. 9, thereby prop- 125 erly positioning the leg with respect to the 130

desk-top and keeping it in place. On two sides, said cleat contacts directly with and presses outwardly the flanges of the side and rear panels 25, 32, thereby effectually preventing said panels from moving out of engagement wth their companion flanges 24 and 26 formed on said leg.

As shown in Fig. 6, the forward vertical edge of each side panel 25 is provided with a return-bend flange 60 adapted to engage with a corresponding flange 61 formed at the rear of the companion front leg 62. This leg has an inner longitudinal wall 63 which is provided with a vertical row of blisters, loops or brackets 64 having vertical apertures 65. These blisters are preferably formed by making a plurality of horizontal slits in said inner wall and then pressing outwardly the metal between them. The blisters need not be of the precise form shown in the drawings, the essential characteristics being ledges or brackets each provided with a vertical aperture.

Located intermediately of each pair of front and rear legs is a vertical supporting post 68 which is preferably constructed of angle iron and arranged to rest on the lower horizontal flange 31 of the adjacent side panel 25, as shown in Fig. 6. This post is secured near its lower end to said flange by a bolt 70 or otherwise. The inner longitudinal wall 71 of the post is provided with a vertical row of blisters or apertured brackets 640 similar to the blisters 64 arranged on the front leg 62. The blisters of said front leg and said supporting post are arranged in horizontal alinement or in sets, so that for every blister 64 on said leg, there is a corresponding blister 640 arranged on said supporting post in horizontal alinement therewith. It will be understood that each pedestal has two of such posts arranged directly opposite each other and that their blisters carry the rear portions of opposing pairs of drawer-slides or guideways 72, while the opposing sets of blisters on the front legs of the pedestal carry the front portions of said slides. As shown, these slides are preferably channel-shaped, and each provided near the rear end of its web with an upwardly projecting tongue 73 which passes through one of the rear blisters, as shown in Figs. 6 and 8. Arranged immediately in front of said tongue and formed in the web of the drawer-slide 72 is an L-shaped slot or notch 74 whose upper longitudinal edge 75 acts as a supporting edge or suspension 75 while the vertical portion of the slot is adapted to terminate a short distance in front of the tongue 73 to admit the front end bar of the blister in engaging the drawer-slide with the latter. Longitudinally in line with the lower edge of said notch and extending rearwardly 65 of said tongue is preferably, though not

necessarily, arranged a step 76 which terminates at the rear end of the drawer-slide. The horizontal part of the notch 74 is just wide enough to receive one of the blisters 640, while the length of the blister-apertures is somewhat greater than the width of the tongue 73. To interlock the rear end of the drawer-slide with any one of the supporting-post blisters, the tongue 73 is moved upwardly into the front portion of the aperture of said blister until the step 76 and the lower edge of the notch 74 come in contact with the lower edge of the blister. Then the drawer-slide is shifted rearwardly, causing its supporting edge 75 to slide upon the 80 blister and rest thereon, as shown in Fig. 6. Vertical displacement of the drawer-slide is thus prevented by the engagement of the upper and lower edges of the notch 74 with the upper and lower faces of the 85 blister while lateral displacement of the slide is prevented by the engagement of the tongue with the blister.

The forward end of each drawer-slide is positively locked to the proper blister 64 of 90 the corresponding front supporting leg. As best shown in Figs. 8, 17 and 18, this engagement is preferably effected by stamping a three-sided or approximately U-shaped slot or opening 77 in the web of the drawer-slide 95 near its front end, to form an integral tongue or key 78 which is adapted to pass downwardly through said blister or apertured bracket, thereby supporting the front portion of the drawer-slide on the blister 100 and at the same time holding the slide against the adjacent leg. The horizontal part of said slot is of sufficient length and width to receive the blister, while the upright branches of the slot are wide enough 105 to receive the end members of the blister. In interlocking the parts, the horizontal part of the slot is passed over the blister and the front end of the drawer slide is then lowered to drop the tongue into the blister. This 110 forms an exceedingly simple and inexpensive locking device which permits the drawer-slide to be quickly shifted from one set of apertured brackets or blisters to another in changing the arrangement of the drawers. 115

A modified construction of this locking device is shown in Fig. 20. In this case, the web of the drawer-slide is provided with a plain horizontal slot 77a for receiving the blister, and the locking tongue or key 78 is 120 replaced by a vertically swinging tongue or key 780 pivoted at 81 to the slide, the free end of the key being adapted to pass through the blister. An upwardly-extending notch 82 is formed in the lower edge of the key 125 to permit it to properly clear the rear edge of the blister.

Adapted to slide longitudinally on said drawer-slides are a plurality of drawers or other suitable filing compartments 84, ex- 130

amples of which are shown in Figs. 2 and 3. Each of these drawers is provided at opposite sides with slide bars 85 which fit into the channels of the drawer-slides, and which 5 are preferably channel-shaped with their grooves 86 facing away from the sides of the drawer. The outer edges of the slide-bar flanges bear against the vertical walls of the drawer slides, and the grooves 86 10 permit the slide bars to clear both the blisters 64 and the modified form of key 780. However, when desired, any drawer with its 15 slide bar may be slid completely out of the desk and then without the use of any tools, the position of the drawer slides may be readily altered, to make the desk efficiently fulfill the desired ends.

88 indicates the lowermost drawer-strike of each pedestal, which also serves to tie 20 its front legs firmly together. These legs are pressed from sheet steel and are substantially U shaped in cross section. Like the rear legs, they are provided with internal rods 52 which clamp the desk top to 25 their upper ends and the foot pieces 46 to their lower ends. As shown in Figs. 1 and 6 the portions of their inner walls 63 below the lowermost drawer-strike 88 are cut away 30 from the rear edges of said walls nearly to their front edges, and those cut-away portions as well as the adjacent rear sides of the front legs are closed by filler pieces 410 35 identical with the filler-pieces 43 of the rear legs. As shown in Fig. 16, the rear vertical flange of each of these filler pieces interlocks with the corresponding flange 61 of the front leg, while the front flange of the 40 filler piece interlocks with a vertical flange 87 bent inwardly from the adjacent narrow portion of the side wall 63.

The drawer-strokes are preferably constructed of channel iron, for lightness and strength, and each end of the strike passes through a rectangular opening 93 formed in 45 the adjacent side wall of the front leg on the rear side of its flange 87 which latter extends to the top of said opening. Said wall is also preferably provided with a vertical notch 94 and a horizontal notch 95 which 50 are adapted to receive an upper vertical flange 96 and the lower flange 91, respectively, of said drawer-strike. The end portion of the lower flange 91 is provided with a hole 97 to receive the adjacent clamping bolt 52 and said flange rests upon the filler piece 410 which sustains the drawer-strike. In the upper and lower flanges 90 and 91 of the drawer-strike are formed vertically-alined notches 92 which interlock with the 55 flange 87, and the face of the wall 63. By this construction the drawer-strokes are rigidly secured in place and the front legs are firmly tied together.

As shown in Fig. 16, the flange 87 is 60 identical in cross section with the other

vertical flanges on both the front and rear legs, so that the same dies may be employed to stamp both the front filler pieces 410 and the rear filler pieces 41.

As shown in Fig. 1, a suitable drawer-strike 59 is located below each of the upper and intermediate drawers 84. In the construction shown, each of said strikes consists of a bar of angular cross section provided at its ends with depending lips or 75 tongues 59^a removably fitted into a pair of the blisters 64.

A modified form of the lower tie bar is shown in Fig. 19 in which a plain-channel bar 98 is employed which however does not 80 function as a drawer-strike. In this construction, the inward movement of the sliding drawers 84 or a safe-door, for example, is limited by a vertical strike-shoulder 100 which is formed on the inner side-wall 630 85 of the front leg 620 rearwardly of its face and against which the usual laterally extending parts of the front walls of the drawers are adapted to strike in an obvious manner. By this means the separate transverse drawer-strokes may be eliminated and drawers of greater depth may be employed inasmuch as the bottom of one drawer may be arranged very closely to the one next beneath it, thereby effecting a further economy of space.

For the purpose of stiffening the pedestals and also excluding dust, it is preferred to employ a horizontal dust plate 101 on the bottom of each pedestal, said plate resting 100 on the lowermost horizontal flanges 31 of the side and rear panels 25, 32, and the flange 91 of the lowermost tie bar or drawer-strike and being suitably secured thereto by 105 screws 102 or otherwise.

Horizontally arranged in the upper part of each pedestal just below the top of the desk is a shelf-support or suspension 102 provided at each longitudinal edge with a depending flange 103 which is secured to the intermediate supporting post 71 by means of a bolt 104 or in any other suitable way, as shown in Figs. 6 and 8. Transversely secured to the shelf-support 102 at the front end thereof is an angle-iron supporting bar 110 110 115 120 125 130 135 140 145 150 155 160 165 170 175 180 185 190 195 200 205 210 215 220 the outer sides of the runways 107 near their base flanges. Thus the shelf slides with comparatively little friction on the runways and is restrained against upward movement by 5 said retaining flanges.

As shown in Figs. 5 and 8, the rear edge of the shelf-support 102 is provided with an upturned flange 114 whose upper edge is adapted to bear against the underside of the 10 desk top 58 and thereby stiffen the same. The rear edge of the sliding shelf 111 is provided preferably with a similar upturned flange 115 to the central part of which is applied a bumper comprising a core 116 which 15 is covered with felt or other suitable sound deadening material 117, this bumper being adapted to strike against the front face of the flange 114 and limit the rearward movement of the sliding shelf. This bumper extends 20 a short distance below the body of said shelf and is adapted to encounter a pivoted stop 118 and thereby limit the outward movement of the shelf. As shown in Fig. 8, this pivoted stop comprises a central ful- 25 crum-portion 120 which is arranged in a transverse slot 121 formed in the central part of the shaft-support 102. Normally ex- 30 tendsing upwardly and rearwardly from said central portion is an upper arm 122 and ex- 35 tendsing downwardly and forwardly there- 40 from is a lower, arm 123, which outweighs the upper arm, so that normally said swinging stop assumes the position shown in the drawings. When however it is desired to com- 45 pletely remove the sliding shelf, the drawer or filing compartment 84 situated immedi- 50 ately below the shelf-support 102 is pulled out a short distance to admit the user's hand, and the lower arm 123 of the pivoted stop is then moved upwardly, thereby with- 55 drawing its upper arm 122 from the path of movement of the bumper and allowing the shelf to be completely withdrawn.

To assemble the desk, the side and rear panels 25 and 32 are first slid downwardly on the flanges of the front and rear legs. Then the front and rear filler piece 410 and 41 are slid upwardly on said legs and the foot pieces 46 fitted in place. The desk top 58 is next placed in proper position against the top of the legs and the clamping bolts 52 are inserted through the holes of the foot pieces 46 and screwed into the holes 53 of the cleats 55 being guided into them by the 55 guide-depressions 49. The intermediate supporting post 68 is then secured at its lower end to the side panel by the bolt 70 and the shelf-support 102 secured at its rear end to said post, and the tongues 106 of said 60 support are dropped into a suitable set of blisters 64. Then the tie bar and drawer strike 88, or the plain tie bar 98, as the case may be, is inserted and if any intermediate drawer strikes 59 are to be employed, the 65 same are secured at their opposite ends to

suitable horizontal sets of blisters 64. Finally, the drawer slides 72 are secured to the proper sets of blisters of each pedestal and proper drawers 84 and the sliding shelf 111 are inserted. 70

Should it be desired to rearrange the drawers or to insert plain shelves, roller book shelves, book stalls, or the like, this can be easily done without the aid of tools. And if it be desired to have one set of drawers 75 facing in one direction and the other set in the opposite direction, so as to make a "two-faced" desk, this can be readily accomplished by reversing one of the pedestals.

As a whole, the desk is obviously light, 80 strong and neat in appearance; it can be readily altered to suit changing requirements; the top is securely held to the supporting legs without any possibility of buckling or warping it, and the drawer slides are effectually prevented from becoming detached, despite the fact that they can be easily removed and applied without the use of tools. The desk is moreover durable 85 and can be manufactured at low cost. 90

While my improvements are herein shown and described in connection with a metal desk, they are obviously applicable to other articles of furniture. 95

I claim as my invention:

1. A metal desk, comprising a desk-top, a hollow supporting leg for the top, longitudinal and transverse panels joined to said leg by interlocking flanges on the vertical edges of said parts, a rectangular cleat secured at its ends to the underside of the desk-top and having its intermediate portion depressed and seated in the top of said leg and bearing at two sides against said flanges to hold them in locked position, and means for securing said cleat in said leg. 100

2. A metal desk and the like, comprising a leg provided with a vertical flange, a panel provided with a flange interlocking with said leg-flange, and a retaining lip on the panel abutting against said leg-flange, said lip being formed by slitting the edge of said panel vertically and bending the adjacent portion of the metal laterally. 110

3. A metal desk and the like, comprising a leg provided with a vertical flange, a panel engaging with said flange, a filler piece also engaging with said flange, and an abutment plate secured to said leg and overlapping the edges of both said panel and said filler piece to hold the same in engagement with the leg-flange. 115

4. A metal desk and the like, comprising a leg provided with return bend flanges along two of its edges, panels engaging with the flanges of said leg, respectively, a filler piece provided with flanges which also engage with said leg-flanges, and an abutment plate secured to said leg and arranged to 120 125 130

- hold both the panels and the flanges of the filler piece in engagement with the return bend flanges of said leg.
5. A metal desk and the like, comprising a leg having opposing walls each provided at its vertical edge with a flange, a filler piece engaging with said flanges, and a drawer-strike arranged above said filler-piece and engaging with one of said flanges.
10. 6. A metal desk and the like, comprising a hollow leg provided in a wall thereof with an opening and adjacent to said opening with an upright flange extending into the leg, said opening being provided in its top with a notch, and a drawer-strike passing through said opening and provided with an upwardly-extending flange arranged in said notch and in its sides with a notch which interlocks with said flange.
15. 7. A metal desk and the like, comprising a hollow leg having the lower portion of one of its walls cut away and provided with an upright flange extending into the leg, a drawer-strike having its end interlocked with the upper portion of said flange, and a filler piece for the cut-away portion of said leg engaging the lower part of said flange and bearing against the lower side of said drawer-strike.
20. 8. A metal desk and the like, comprising a hollow leg having the lower portion of one of its walls cut away and provided with an upright flange extending into the leg and adjacent to the upper end of said flange with an opening, a drawer-strike fitted in said opening and interlocking with said flange, and a filler piece for said cut away portion engaging with said flange and supporting the drawer-strike.
25. 9. A metal desk and the like, comprising a leg having opposing walls, one of said walls being provided in its lower portion with an opening and having the portion thereof below said opening partly cut away, said opening extending to the lower edge of the intact portion of said wall, the cut-away portion of said wall having a vertical flange extending into the leg and upwardly along the side of said opening, a drawer-strike passing through said opening and interlocking with the upper portion of said flange, the opposing wall of the leg being provided at its edge with a vertical flange, and a filler piece for the lower cutaway portion of the leg arranged beneath the drawer-strike and having flanges which interlock with the flanges of said opposing walls.
30. 10. A metal desk and the like, comprising opposing upright front supports each provided with a vertical row of apertures, opposing upright rear supports each provided with a vertical row of apertures, the apertures of said front and rear rows being in horizontal alinement, shiftable drawer-slides engaging with their opposite ends in a set of said front and rear apertures, and shiftable tie bars arranged at right angles to said drawer-slides and engaging with their opposite ends in one of said sets of front apertures.

ION A. STAFFORD.
